UNITED STATES PATENT OFFICE

CHARLES A. MULLEN, OF NEW YORK, N. Y., ASSIGNOR TO RUTH DAVIS MULLEN, OF NEW YORK, N. Y.

DRYING AND HEATING APPARATUS.

1,074,519.

Specification of Letters Patent. Patented Sept. 30, 1913.

Application filed June 30, 1910. Serial No. 569,783.

To all whom it may concern:

Be it known that I, CHARLES A. MULLEN, a citizen of the United States of America, residing at 17 West Twenty-fourth street, New York city, in the county of New York and State of New York, have invented certain new and useful Improvements in Drying and Heating Apparatus, of which the following is a specification, reference being had therein to the accompanying drawing.

This invention relates to improvements in drying and heating apparatus for treating gravel, sand, grit, broken stone, or other like granular substances, the principal object being to provide an apparatus which will effectually remove the moisture from and sufficiently heat the material by a continuous process for its utilization in constructing, renovating or repairing roadways, roofs, composition pavements, as a filler in joints of block pavements, and in all industries requiring the granular material in a heated and dried condition.

In constructing all of the drying and heating apparatus of the general type of this invention, they have ignored either the advantage and necessity of gravitating the material to be dried and heated directly over the side of the furnace, or the advantage and necessity of gravitating said material in a thin and approximately even layer through which the heat or products of combustion may readily penetrate. It is therefore proposed in the present invention to provide a gravitating, drying and heating apparatus which includes a furnace, and a drying and heating compartment having sides so arranged as to contain a thin and approximately even layer of the material to be dried and heated, said compartment arranged about said furnace so that the inner side of the compartment is the side of the furnace.

The invention further consists of certain novel details of construction and combinations and arrangement of parts, all as will be now described and the particular features of novelty pointed out in the appended claims.

In the drawings:—Figure 1 is a perspective view of my improved drying and heating apparatus, a portion of one of the end plates being broken away, Fig. 2 is an end view of the same shown partly in section,

Fig. 3 is a side elevation of the drying and heating apparatus.

In carrying this invention into practice, and having particular reference in this instance to Figs. 1, 2 and 3 of the drawings, I make use of a furnace, having two sides *a*, *a'*, preferably perforated, and so arranged roofwise as to resemble in cross section, an inverted letter V, and two end plates *b*, *b'*, a fire door *c* being provided in one of the end plates, and a flue *d* with a damper *e*, extending from the other end plate for carrying off products of combustion. It will be noted that the end plates *b* and *b'* extend some distance beyond the perforated sides of the furnace, and thus serve as end plates for the heating and drying compartments, which compartments are arranged at the sides of said furnace. The end plates are secured in proper position relative to the sides of the furnace by means of angle irons *f* to which the said sides and end plates are securely bolted or riveted.

As has heretofore been pointed out, the drying and heating compartments are such as to accommodate therein, a very thin layer of the material to be dried, and the sides of the furnace form the inner sides of said compartments, the outer side of each compartment being made up of a series of downwardly and inwardly deflecting flights *g*, which are preferably perforated, and which are arranged in a line slightly separated from the sides of the furnace and approximately parallel thereto, extending from the top to a point slightly above the base of the furnace. These flights are of approximately the same length as the furnace sides, and are secured at their ends to the extensions of the end plates by means of angle irons *h*, which angle irons are also bolted or otherwise secured to the top edges of said flights. As a further support for these flights, one or more bars or strips in the form of inverted T irons *i* are bolted or riveted to the sides of the furnace, which T irons are provided with vertical slots *j* within which the flights are supported.

A suitable hopper *k* is arranged above the apex of the furnace structure, and is secured in place by bolts or rivets to the uppermost flight on each side of the furnace, and to the end plates of said furnace, said

hopper adapted to receive the material which it is desired to dry and heat, and feed the same into the two compartments through the openings formed at the upper edges of the furnace sides and the uppermost flight 5 on each side of the furnace. As has been stated, the lower flight on each side of the furnace is arranged a slight distance from the base of said furnace, and in this way 10 an exit for the material being dried and heated, is formed, so that the material is discharged, if it be desired, in a pile on the ground at the base of the furnace sides, from whence it may be taken in a dried and 15 heated state ready for use.

It will thus be seen that the material to be dried and heated is fed in at the hopper until it has filled the two compartments and supplied a sufficient quantity at the exit 20 opening to choke the flow of the material. As the material in the heating and drying compartment becomes thoroughly heated and dried, that which has at first fallen through the exit on to the ground, is again 25 replaced in the hopper, it having not as yet been treated, allowing the heated and dried material to fall in its place and be removed for use, when, as fast as it is removed, an equal quantity from the untreated supply 30 must be added at the hopper, thus creating a continuous gravitating process during which the desired result is accomplished.

The grate of the furnace is illustrated at 1 and said grate is supported on angle irons 35 *m*, one on each side of the furnace, which are secured at their ends to the end plates *b* and *b'*. Caster wheels *n* are provided at the four corners of the furnace structure, and are preferably secured to the end plates as 40 shown, and in this manner the heating and drying apparatus is made portable and can be easily carried along as the work progresses, a handle *o* being provided for moving said apparatus when desired.

45 In using my improved drying and heating apparatus, and after the fire in the furnace is well started, I close the damper in the flue, thus requiring the products of combustion and heat to be forced out through 50 the perforations in the furnace sides, through the gravel, and then through the perforations in and the spaces between the downwardly and inwardly deflecting flights. By thus using the apparatus, a more, com- 55 plete utilization of all the heat and products of combustion can be had, for the reason that they cannot escape doing their work of drying and heating on their way out through the perforated sides, and through the gravel, 60 they having no means of escape except by these passages.

The hopper may be of any convenient shape that will discharge the material to be dried and heated through an opening in its 65 bottom into the openings at the top of the

drying and heating compartments, and if desired, a storage bin *p*, such as shown in Fig. 2 of the drawings, may be placed below the exit at the bottom of said drying and heating compartment or compartments to receive and contain the discharged material until the same is needed for use. 70

Having thus fully described my invention, what I claim and desire to protect by Letters Patent, is:—

75 1. In a gravitating drying and heating apparatus, the combination of a furnace having sides and end plates, metal bars or strips secured upon the exterior of the sides of said furnace and transversely arranged thereon at intervals throughout the length of the sides, and a series of flights arranged lengthwise of the furnace and supported by said bars or strips, said flights forming with said furnace sides a compartment through 80 which the material to be dried and heated may pass in a thin and approximately even layer.

85 2. In a gravitating drying and heating apparatus, the combination of a furnace having sides and end plates, metal bars or strips secured upon the exterior of the sides of said furnace, and a series of flights arranged adjacent said furnace sides in spaced relation therewith and being supported by 90 said bars or strips, said flights forming with said furnace sides a compartment through which the material to be dried and heated may pass in a thin and approximately even layer. 95

100 3. In a gravitating drying and heating apparatus, the combination of a furnace having sides and end plates, metal bars or strips secured upon the exterior of said furnace sides and having slots formed therein, and a series of flights arranged adjacent said furnace sides in spaced relation therewith and engaging within said slots, whereby they are supported and held in position, said flights forming with said furnace sides 105 a compartment through which the material to be dried and heated may pass in a thin and approximately even layer.

110 4. In a gravitating drying and heating apparatus, a furnace consisting of a perforated sheet of metal bent over roofwise to form two heating sides arranged directly above the floor of said furnace, end plates secured to the edges of said sides, said end plates having extensions which project beyond the sides of the furnace, and a series of flights arranged lengthwise of the furnace at spaced intervals therefrom, said flights being secured and supported by the 115 said extensions of the end plates, and said flights and the sides of the furnace forming a drying and heating compartment for containing a thin approximately even layer of the material to be treated. 120

125 5. In a gravitating drying and heating 130

- apparatus, the combination of a furnace having sides and end plates arranged above the fire of said furnace, said end plates having extensions which project beyond the 5 sides of the furnace, downwardly and inwardly directed flights arranged lengthwise of the furnace and approximately parallel to its sides, said flights being secured to the said extensions of the end plates, which extensions 10 serve as the end walls of a compartment which is formed between the sides of the furnace and the flights, and a hopper arranged above the furnace and adapted to feed the material to be treated to the drying 15 and heating compartment.
6. In a gravitating drying and heating apparatus, the combination of a furnace having sides and end plates, said end plates having extensions which project beyond the 20 sides of the furnace, downwardly and inwardly directed flights arranged lengthwise and approximately parallel to its sides, said flights being secured to the said extensions of the end plates of the furnace, which extensions 25 serve as the end walls of a compartment which is formed between the sides of the furnace and the flights, and partitions arranged within the compartments and serving to support the flights.
- 30 7. In a gravitating drying and heating apparatus, the combination of a furnace having sides and end plates, a drying and heating compartment arranged about the furnace, angle irons arranged lengthwise of
- the furnace along the sides thereof and secured at their ends to the end plates, and a furnace grate supported on said angle irons. 35
8. In a gravitating drying and heating apparatus, a drying and heating compartment constructed to contain a thin approximately even layer of the material to be dried, said compartment having perforated sides and being so arranged in relation to the furnace or fire box that the direct heat and products of combustion from said fire box will be drawn through the gravel by the draft passing out through the perforations in the sides of the heating and drying compartment, thus taking off the moisture 40 and heating the material. 45
9. In a gravitating drying and heating apparatus, the combination of a furnace having sides and end plates, metal bars or strips secured upon the exterior of the sides of said furnace and transversely arranged thereon at intervals throughout the length of the sides, and a series of flights arranged lengthwise of the furnace and forming with said furnace sides a compartment through which the material to be dried and heated 50 may pass in a thin and approximately even 55 layer. 60

In testimony whereof I affix my signature in presence of two witnesses.

CHARLES A. MULLEN.
